UNITED STATES PATENT OFFICE.

ALPHONSE MAYR AND JOHN WALLACE, OF BOMBAY, INDIA.

HOT-AIR ENGINE.

No. 876,374.

Specification of Letters Patent.

Patented Jan. 14, 1908.

Application filed October 4, 1907. Serial No. 395,948.

To all whom it may concern:

Be it known that we, ALPHONSE MAYR, a subject of the Emperor of Austria, and JOHN WALLACE, a subject of the King of England, both residing at Bombay, in the Empire of India, have invented certain new and useful Improvements in or Relating to Hot-Air Engines, of which the following is a specification.

10 The object of this invention is to increase the efficiency and working economy of hot air engines, more especially such as are used to operate ventilating fans and for other light work.

15 An apparatus embodying the present invention comprises a hot air engine with two cylinders known respectively as the working and the displacer cylinder, the latter being suspended over a source of heat. This cylinder is divided into an upper or cooling part, and lower or heating part, by means of a ring of non-conducting material which forms part of the cylinder and which retards the passage of heat from the heating to the cooling part 25 of it. The working cylinder is attached to the displacer cylinder but at the junction a liner of slow heat-conducting material is interposed to retard the passage of heat between the cylinders. The displacer piston 30 is a closed hollow cylinder, having near the middle of its length a diaphragm of non-conducting material which separates it into two parts, and retards the passage of heat from one to the other. This piston is connected 35 by means of piston and connecting-rods to the crank shaft. The working cylinder has a trunk-piston connected by means of a rod to a separate crank on the end of the shaft. A suitable air passage connects the two cylinders and the inclosed air circulates between them.

40 The displacer cylinder is suspended in a stand or pillar containing a lamp or other source of heat, and this stand is lined where required, with non-conducting material to prevent loss of heat by radiation. The heat acts first on the lower end of the displacer cylinder and then passes upwards around it in a flue to an annular space around the non-conducting ring, it then escapes into a chimney which carries away the products of combustion. This chimney may be fitted with a damper to regulate the draft or escape of spent gases. A non-conducting covering 45 is placed around the upper part of the displacer cylinder to arrest the loss of heat,

which comes very slowly past the non-conducting ring.

A convenient construction embodying the invention will now be described, by way of example, with reference to the accompanying drawings, showing a central vertical section of the apparatus.

The two cylinders are placed side by side and connected to a common crank shaft *o*.
65 The upper or cooling part *a*, of the displacer cylinder is prolonged so as to carry the crank shaft and to its side is attached the working cylinder *b*, a passage *q* opening into the bottom of the latter cylinder making communication between them; an insulating plate *a*² of heat-insulating material separating the cylinders at the point of communication. A flange *a*³ on the part *a* of the displacer cylinder rests upon a sheet metal stand *i*, forming 70 the base of the machine, and beneath this flange is a ring *k*, of non-conducting material which separates the heating or lower part *f*, of the displacer cylinder from the cooling part *a*. The connection between the two parts is made by means of bolts passing through the flanges *j* and *a*³, which reduce the metallic connection between the upper part *a*, and the lower part *f*, of the displacer cylinder; the latter being made preferably of 75 copper. The escaping heat while traversing the annular passage around the non-conducting ring, impinges against the horizontal flange *a*³ of the cooling part *a*, and communicates to it the small amount of heat necessary 80 to prevent the air from becoming so cool that it cannot absorb its proper charge of heat during the short interval of exposure to the hot surfaces at *f*.

The displacer piston *d*, is a closed cylinder 95 of thin metal cut and joined by a diaphragm *e* of earthenware or other non-conducting material, which breaks the metallic continuity of the piston and retards the passage of heat from below upwards. The displacer 100 piston *d*, and the working piston *c*, are connected to their respective cranks by connecting rods *m* and *n*, and the cooling part *a*, of the displacer cylinder is closed with a non-conducting coating *a'* to conserve the reduced amount of heat it receives from the heating part. A lining *h*, of non-conducting material is fixed within the metal casing *i*, and surrounds the part *f*, of the displacer cylinder. It is pierced at *g*, by a sight hole 105 covered with mica which allows the flame of the lamp *r*, to be seen. A plate *s* closes the 110

bottom of the lining *h*, and has an orifice to admit the burner of the lamp *r*. There is thus a continuous protected passage for the products of combustion from the flame along 5 the bottom and sides of the displacer cylinder *f*, through the annular chamber around the non-conducting ring *k*, and out by the chimney *y*, by which the products of combustion are conveyed away to a sufficient distance.

10 The damper *t*, serves to regulate the current of spent gases.

The mode of operation of the working and displacer pistons is that of a closed hot air engine of similar construction. The effect 15 of the special insulation is as follows:— The working charge of air is heated between the lower part of the displacer cylinder and its piston and as the non-conductors dividing the displacer cylinder and its piston retard 20 the upward passage of the heat by conduction, the temperature of the lower part of these members is increased and the air exposed to them reaches a higher temperature and is more rapidly heated and expanded 25 than if these non-conductors were not used. In order to keep the upper part of the displacer cylinder and its piston cool the non-conducting ring in the displacer cylinder and the diaphragm in the displacer 30 piston are of such a depth, and so placed, that the hot lower part of the displacer piston never rises beyond the non-conducting ring in the displacer cylinder and the cool upper part of the displacer piston never 35 passes below the ring. The transmission of heat from the hot lower part of the displacer cylinder and piston to their upper parts is therefore reduced to a minimum. The latter parts remain cool and take up and 40 dissipate readily without a water jacket or radiators, the small amount of heat contained in the rising working air. When the engine is small, or the air about it is cold, the radiation may require to be mitigated 45 by a non-conducting covering *a'* around the cylinder *a*, to prevent it from becoming too cool for efficient working. The invention is applicable equally when the cylinders are parallel or in line.

50 What we claim as our invention and desire to secure by Letters Patent is:—

1. In a hot air engine a working cylinder and piston, a displacer cylinder comprising a heating part and a cooling part, and a heat insulating part between the heating and cooling parts in combination with a displacer piston consisting of two parts separated by an insulating section, substantially as set forth.
- 60 2. In a hot air engine a displacer cylinder comprising an upper cooling part and a lower metallic heating part and an intermediate heat insulating portion separating the upper

and lower metal portions in combination with a displacer piston consisting of upper 65 and lower metal parts and a separating heat insulating part and a working cylinder connected to the displacer cylinder and a separating insulator between the two cylinders substantially as set forth.

3. In a hot air engine a working cylinder and piston, a displacer cylinder comprising a heating part and a cooling part, and a heat insulating part between the heating and cooling parts, an insulating covering around 70 the cooling part in combination with a displacer piston consisting of two parts separated by an insulating section, substantially as set forth.

4. In a hot air engine a displacer cylinder 80 comprising an upper cooling part and a lower metallic heating part and an intermediate heat insulating portion separating the upper and lower metal portions, an insulating covering around the cooling part, in combination 85 with a displacer piston consisting of upper and lower metal parts and a separating heat insulating part and a working cylinder connected to the displacer cylinder and a separating insulator between the two cylinders 90 substantially as set forth.

5. A hot air engine comprising a displacer cylinder consisting of two metallic parts and an intermediate insulating part, a piston in 95 said cylinder comprising two metallic parts and a separating intermediate heat insulating part in combination with a working cylinder supported on the side of the displacer cylinder, insulating plates between the adjacent portions of the working cylinder and displacer cylinder, and a heat insulating covering about the upper end of the displacer cylinder substantially as described.

6. A hot air engine comprising a displacer cylinder consisting of two metallic parts and an intermediate heat insulating part, a piston in 100 said cylinder comprising two metallic parts and a separating intermediate heat insulating part in combination with a working cylinder supported on the side of the displacer cylinder, insulating plates between the adjacent portions of the working cylinder and displacer cylinder, and a heat insulating covering about the upper end of the displacer cylinder, substantially as described.

In testimony whereof we have signed our names to this specification in the presence of 115 two subscribing witnesses.

ALPHONSE MAYR.
JOHN WALLACE.
